PHOTOGRAPHIC DEVELOPING MACHINE

Samuel Hershberg, Brooklyn, N. Y.

Application June 8, 1935, Serial No. 25,647
Renewed August 3, 1938

11 Claims. (Cl. 95—89)

This invention relates generally to photographic developing machines and more particularly to such machines wherein all of the photographic finishing processes are completed automatically.

The main object of this invention is the provision of structure wherein great economy of operation is afforded, together with an increase in the size and quality of finished pictures. All this is accomplished by virtue of a compact and conjunctive arrangement of the various sub-assemblies; a saving in the cost of chemicals by eliminating inter-tank pollution; a saving in labor costs owing to the automatic operation of the machine, and the manipulation and transfer therethrough of the sensitized material; and by virtue of the production of a higher average of perfect prints, the result of precise timing of the development steps and exact mechanical manipulation thereof.

Another object of this invention is the provision of structure permitting the light-proof communication between this developing machine and a camera, capable of movement independently of the said machine.

A further object of this machine is the furnishing of means whereby individual sheets of sensitized material, larger than heretofore, are manipulated through the developing machine without the use of backing pieces or frames to reinforce the said sheets or without the necessity of feeding the developing machine with long continuous strips of sensitized material.

These objects, further features, and other incidental ends and advantages will more fully appear in the progress of this disclosure and as pointed out in the appended claims.

In the accompanying drawings similar reference characters denote similar parts throughout the several views:

Figure 1 is a fragmentary side elevational view of the machine with the outer casing thereof removed.

Figure 2 is a fragmentary plan view, with the greater portion of the intake conveyor broken away.

Figure 3 is an enlarged fragmentary front elevational view showing the magazine and clip loading mechanism.

Figure 4 is a fragmentary sectional view of Figure 3 along the line 4—4 thereof showing one of the paper retaining pawls or dogs.

Figure 5 is a fragmentary sectional view of Figure 3 along the line 5—5 thereof showing one of the clips and actuating mechanism therefor.

Figure 6 is a fragmentary sectional view of Figure 7 along the plane 6—6 thereof showing the rear portion of the loading magazine with the rear stationary wall thereof broken away.

Figure 7 is a fragmentary sectional view of Figure 8 along the plane 7—7 thereof, showing the loading magazine in end elevation.

Figure 8 is an enlarged fragmentary plan view of the loading magazine.

Figure 9 is a vertical sectional view of Figure 8 along the plane 9—9 thereof, showing the upper portion of the magazine, as well as the lower portion of the magazine inlet chamber.

Figure 10 is an enlarged fragmentary plan view of the electro-mechanical timing device.

Figure 11 is an enlarged sectional view of Figure 10 along the line 11—11 thereof.

Figure 12 is an enlarged sectional view of Figure 10 along the line 12—12 thereof.

Figure 13 is an enlarged sectional view of Figure 10 along the line 13—13 thereof.

Generally speaking, the invention contemplates a rectangularly shaped box-like casing which encloses the developing machine, said casing having an angularly disposed top wall. A camera adapted for movement along the top wall maintains a light-proof connection therewith and deposits exposed sheets of sensitized material upon a moving conveyor in the developing machine casing. All this is clearly set forth in co-pending applications for Letters Patent by the same inventor as follows: System of photography, filed September 15, 1934, Serial Number 744,225; Photographic developing machine, filed September 21, 1934, Serial Number 744,886; Camera, filed September 21, 1934, Serial Number 744,887. The sensitized sheets are then carried through the machine by mechanism to be described below and deposited into a receptacle as finished prints or pictures.

The aforesaid box-like casing is composed of removable lightproof sidewalls detachably affixed to a skeletal framework of angle iron, and the various assemblies in the machine are suitably supported from said framework. Numeral 20 designates one of the horizontal longitudinal angle irons, there being two, which constitute the longitudinal base members of the machine and support therebetween a base plate 21 forming the flooring of the machine.

Power source

An electric motor 22, preferably operating at 1750 R. P. M., constitutes the main motive power source of the machine. Motor 22 is positioned

50

45

30

35

40

45

50

55

medially and to one side on the floor of the machine, on a pedestal 23 therefor. The main shaft 24 of motor 22 is longitudinally and horizontally disposed, and communicates with a speed reduction gear box 25. Gear box 25 has two external reduced speed drive shafts, 26 at approximately 36 R. P. M. and 27 at approximately 4 R. P. M.

Shaft 26 is disposed horizontally and transversely of the machine, while shaft 27 is disposed 10 longitudinally and is journaled at its forward end in a bearing support 27'.

Sheet intake conveyor

Numeral 28 designates a continuous conveyor belt operating longitudinally and pitched as shown in Figure 1, and thus travels parallel to and below the tracks 29 which carry a camera or other depositing equipment. The belt 28 is carried by a pair of rollers, only the lower driving 20 roller 30 being shown, and both rollers are suitably trunnioned in brackets affixed to the framework adjacent thereto, said brackets not being shown in the accompanying drawings. Roller 30 is mounted upon a spindle 31 having a sprocket 25 affixed at each end thereof. The sprocket 32 affixed to the outer end of spindle 31 is connected by a chain 33 to a sprocket 34 mounted on shaft 26. Spindle 31 operates at approximately 43 R. P. M.

Magazine and magazine inlet chamber

Situated forward of and below the lower bight of belt 28 is a magazine inlet chamber 35 comprised of a rear wall 36, a forward wall 37, and 35 two side walls which are forward portions of two large vertical and parallel spaced plates 38 and 39. Plates 38 and 39 extend up and rearwardly to form side walls for the conveyor belt 28 and thus prevent any undesirable transverse displacement of the sheets of sensitized material being carried on the said belt. The rear wall 36 is transversely and vertically disposed, while the middle portion thereof is gently bent in two opposed right angles so that the lower portion of said 40 wall is rearwardly offset and parallel to the upper portion, and constitutes the rear wall 40 of the magazine 41. Immediately to the rear of the forward wall 37 are mounted a pair of frustum rollers 42. Rollers 42 each have a flattened portion, and the axes of the said rollers are in a 45 vertical plane parallel with front wall 37. Both of the rollers 42 rotate in synchronism at approximately 33 R. P. M., in the same direction, the flat faces thereof always parallel. Said rollers 45 derive motion from spindle 31 by means of a pulley 43 on spindle 31, a belt 44, a pair of idler pulleys 45, a double pulley 46 on one of the rollers 42, a connecting belt 47, and a pulley 48 on the other one of the rollers 42.

The bottom of the magazine inlet chamber 35 is a gently curved convex plate 49, the configuration thereof being best shown in Figure 9. Plate 49 is pivotally mounted at the forward upper edge thereof, by means of two downwardly projecting integral bosses 50 co-axially penetrated by a spindle 51, the latter penetrating the side walls formed by plates 38 and 39 and being suitably trunnioned at its ends in horizontal bearing supports 52 and 53, said supports projecting rearwardly from the front skeletal framework. Integral with bosses 50 are two irregularly shaped pusher fingers 54, which extend downwardly and are then upwardly and arcuately bent to the rear as best seen in Figure 9. The plate 49 and fingers 75 54 are caused to oscillate by means of the bell-

crank lever 55 and cam 56. Lever 55 is provided with laterally projecting integral studs at each end thereof, each carrying a roller. The upper roller bears against the under surface of plate 49, while the lower roller acts as a follower for cam 56. The lever is radially mounted upon a shaft 57 which after penetrating plates 38 and 39 is suitably trunnioned in supports 52 and 53, the details of said trunnioning being omitted from the drawings for the purpose of clarity. Cam 56 is mounted upon a transverse shaft 58 which similarly penetrates plates 38 and 39 and is journaled in supports 52 and 53. Shaft 58 is driven by sprocket 59, concentrically affixed thereto adjacent its inner terminal, a connecting chain 15 60, and a sprocket 61 concentrically affixed to spindle 31 adjacent the inner end thereof. Shaft 58 rotates at approximately 22 R. P. M.

The floor of magazine 41 is formed by a horizontal shelf 62 suitably supported from the skeletal framework adjacent thereto, and extending laterally sufficient to form a flooring for the clip loading mechanism as will be more particularly described below. Situated within the magazine 41 directly in front of rear wall 40 and at 25 a height above shelf 62 slightly greater than the width of a sheet of sensitized material stood on edge therein are a pair of pawls or dogs 63. Dogs 63 are pivotally mounted by reason of their affixation to a shaft 64 which is trunnioned similarly to shaft 57 set forth above. The lower terminals of dogs 63 are wedge shaped and downwardly pointed, while the upper terminals thereof are provided with laterally projecting studs with rollers thereon which serve as followers for a 30 pair of cams 65 mounted on a shaft 66. Shaft 66 is trunnioned similarly to shaft 57 set forth above and adjacent its outer end carries a gear 67 which engages a gear 68 carried by shaft 58, thus deriving its rotation from shaft 58. The 40 rotation of shaft 66 causes dogs 63 to rock as best seen in Figure 4.

The rear wall 40 of magazine 41 has a horizontal rectangular slot therein and within said slot a resiliently faced plate 69 is adapted for 45 transverse reciprocation. Plate 69 is provided with two longitudinal flanges 70 which engage corresponding channels in a guideway plate 71 supported horizontally and transversely of the machine by two uprights 72 vertically projecting 50 from shelf 62. Guideway plate 71 contains a horizontal slot 73, so that a stud 74 integral with plate 69 projects rearwardly from said plate through the slot 73. A link bar 75 is pivotally connected to a crank 76 and the stud 74. Crank 76 is radially affixed to the forward end of a 55 short shaft 77 which is journaled in two uprights 78 and 79 projecting from shelf 62. A horizontal plate 80 carries a resilient facing 81 and is supported by an integral downwardly bent 60 arm 82 offset at a 90 degree angle thereto. Horizontal plate 80 and arm 82 are adapted for vertical reciprocation by reason of the slideable mounting of arm 82 in the upright 83. Arm 82 has longitudinal flanges which engage a corresponding vertical channel guideway in the upper portion of upright 83. The said channel in upright 83 is open to the rear to permit the projection therethrough of a short stud 84 which projects rearwardly from the lower end of arm 82 and serves a follower for the cam 85 mounted on shaft 77. Stud 84 is maintained in operative engagement with cam 85 by the contractile spring 86 connecting plate 80 and upright 79. Rotation 70 of shaft 77 thus causes plate 69 to laterally re- 75

ciprocate and plate 80 to vertically reciprocate. Shaft 77 derives rotation through a sprocket 81 thereon, a connecting chain 88, and a sprocket 89 mounted immediately to the rear of upright 27' on shaft 27.

The forward wall of the magazine 41 is formed by a rectangular compressor plate 90, vertically and transversely disposed, and adapted for forward and rearward reciprocation. Compressor plate 90 is provided with two integral and parallel rods 91 projecting perpendicularly from the front face thereof, and these rods are slideably mounted in the orificed upper ends of two uprights 92 vertically projecting from shelf 62. Plate 90 also contains two vertically disposed slots 93 to permit the rearward penetration therethrough of the pusher fingers 54.

An irregularly shaped bell-crank lever 94 is pivotally mounted below magazine 41 for movement in a vertical plane, by means of a short integral axle which is journaled between the upper ends of a bifurcated upright support 95. A stud 96 on the upper end of lever 94 contacts plate 49 and displaces it upwardly and rearwardly when lever 94 is actuated, while the pivotal connection of lever 94 to plate 90 through the sliding clevis assembly 97, causes a concurrent rearward displacement of plate 90. In assembly 97 the clevis is integral with plate 90 while the clevis pin penetrates a slot in lever 94 thereat. The rear and lower end of lever 94 is provided with an integral stud and roller thereon which serves as a follower for the actions of the upper arm of a rock-lever 98. Bell-crank lever 94 is maintained in operative engagement with rock-lever 98 by the action of a contractile spring 99 connecting the lower arm of lever 94 and the upright support 95. Rock-lever 98 is pivotally mounted for movement in a vertical plane, by means of a short integral axle which is journaled between the upper ends of a bifurcated upright support 100. Supports 95 and 100 project perpendicularly from base plate 21. The lower and rear arm of rock-lever 98 is provided with an integral stud and roller thereon which serves as a follower for a plate cam 101, approximating a semi-circle in shape, and mounted upon a long transverse shaft 102. The configuration of cam 101 is best seen in Figure 1, but it is omitted from Figure 2 for purposes of clarity. Shaft 102 is journaled in two uprights 103 and 104 at the ends thereof, and derives rotation through a sprocket 105 mounted thereon adjacent upright 103, a chain 106, and a sprocket 107. Sprocket 107 is mounted on a short transverse shaft 108 journaled in uprights 109 and 110 perpendicularly projecting from base plate 21, just forward of the speed reduction gear box 25. Short shaft 108 penetrates upright 110 and projects therethrough to have concentrically mounted upon the inner end of said shaft a bevel gear 111 which engages another bevel gear 112 the latter bevel being concentrically mounted upon shaft 27 just forward of box 25. Shaft 108 operates at one half the speed of shaft 27, and shaft 102 operates at the same speed as shaft 108 so that shaft 102 operates at the speed of approximately 2 R. P. M.

The finishing tanks

Numerals 113 to 120 inclusive indicate a plurality of tanks arranged in a row. The number of tanks is arbitrary, and depends upon a consideration of the type of development process to be used or upon limitations of space. The

several tanks are supported in operative position in any suitable manner such as by nesting them in brackets projecting from the floor of a drainage trough 121. Trough 121 has vertical longitudinal side walls, and a vertical front wall, 5 while the rear wall thereof is angularly disposed. The bottom of trough 121 is not horizontal, so that drainage will be accomplished, and a suitable outlet leading to a sewer or other disposal means communicates with the trough at its lowest point, said outlet not being specifically shown in the drawings. Trough 121 is supported by attachment to the skeletal framework adjacent thereto. The contiguous front and rear walls of the tanks 113-120 contact each other at the 15 upper edges thereof, but converge so that the bottom of each tank is reduced in size. The side walls of the tanks are parallel and vertical. Each of the tanks is provided with a manually controlled petcock 122 in the bottom thereof, 20 while communicating with the mouth of each tank is an inlet pipe 123. Pipes 123 connect with the water supply 124 and are each provided with a manually operable control valve. The ends 25 of the inlet pipes 123 and the water supply 124 are shown in the drawings, but the connection therebetween and the control valves, being usual, are omitted for the sake of clarity.

Situated between tanks 118 and 119 is a light-proof re-exposing box 125 normally kept closed at 30 the mouth thereof by an overlapping gate 126 and an underlapping gate 127. The forward edge of gate 126 and the rear edge of gate 127 are hinged slightly below the mouth of box 125 to the front and rear walls, respectively, of said box. The free edge of gate 126 is notched as will be set forth in detail below. The hinged edges are adapted for pivotal movement by virtue of their radial affixation to two transverse spindles 128 which are journaled in orifices in the side walls 40 of box 125. Spindles 128 project through the outer side wall of box 125 and have cranks 129 radially affixed to the outer ends thereof. The free ends of cranks 129 carry integral studs and rollers thereon which serve as followers for the 45 cam surfaces on an actuating plate 130. Plate 130 is vertically disposed, parallel to the outer side wall of box 125, and is supported in position by an inwardly bent integral right angled arm 131, said arm being affixed to the under surfaces of the longitudinal tie bars of the transfer carriage, as set forth below. Plate 130 has two parallel operating edges 132, and two converging operating edges 133, as best seen in Figure 1 where it is shown in its lowered position. As plate 130 is 50 raised, converging operating edges 133 act as cam surfaces and force cranks 129 apart thereby opening gates 126 and 127, while the parallel operating edges 132 keep the gates open as the plate 130 is 55 raised farther. The descent of plate 130 reverses this procedure, the action of gravity upon gates 126 and 127 being aided by a contractile spring interconnecting the studs on the free ends of cranks 129. Re-exposing box 125 has the 60 lowermost portion of the forward wall thereof expanded to contain an incandescent bulb 135 or other illuminating source, and within said box adjacent said bulb, an angularly disposed translucent plate 136 mounted inwardly and downwardly from the inner surface of the said forward 65 wall. Plate 136 serves to diffuse the light emitted from bulb 135 during the re-exposing process so that uniform illumination is obtained on the actinic surface of a sheet of sensitized material suspended in box 125. Where a development process 70

75 to be used or upon limitations of space. The

76

is used in which re-exposure is not necessary or is otherwise undesirable the box 125 and the other parts integrally attached thereto may be completely removed and another tank identical to the others may be substituted. Vertical reciprocation of plate 130 will then have no operative effect.

Situated forwardly of tank 113 and in association therewith is an enclosed electrical heater 137 which is used to alter the temperature of the chemical solution in said tank. Numeral 138 denotes a similar heater associated with tank 114. These heaters may be placed adjacent any of the tanks whenever desired, in the interstices formed owing to the downwardly converging front and rear walls of the tanks. The energization of the heater units is controlled either thermostatically and/or predeterminedly, although the structure as shown displays the latter type of control. Numeral 139 designates a thermometer having its sensitive element immersed in tank 113 and its recording or indicating element external to the machine casing. Similar instruments may be used with any of the other tanks where temperature control is deemed sufficiently important.

25   *The transfer carriage*

For the manipulation of the sheets of sensitized material through the various steps of development a transfer carriage 140 is positioned above the row of tanks 113-120. The carriage 140 comprises generally a substantially rectangular frame horizontally and longitudinally disposed and adapted for vertical reciprocation and carrying thereon an endless chain adapted for intermittent motion in synchronism with the oscillations of the rectangular frame. The endless chain in turn carries the clips which are capable of limited independent movement and carry the sheets of sensitized material in their jaws.

40   Numerals 141 and 142 represent inner and outer horizontal longitudinal tie bars which are rigidly affixed to two non-rotating transverse axles 143 and 144 by means retaining hubs 145. Axles 143 and 144 are horizontal and project inwardly from offset bosses 146 which constitute 90 degrees angle 45 elbows of sleeves 147, as best shown in Figure 3. Sleeves 147 are slideably mounted upon two upright rods 148 and are thus capable of vertical displacement thereon. Rods 148 are rigidly mounted in parallel and vertical position by pedestals at the bottoms thereof, affixed to base plate 21 thereunder, while the upper terminals of said rods are inter-braced by a horizontal tie bar 149 affixed thereto by hubs 150.

55   The rear axle 144 has concentrically mounted thereon a large idler sprocket 151 which though free to rotate is prevented from lateral displacement. Forward axle 143 has similarly mounted thereon a large driving sprocket 152, which integral with the hub 153 thereof has an expanded concentric flange 154. Flange 154 has concentrically mounted upon the outer face thereof a ratchet wheel 155 having four equi-distant peripheral teeth. Outwardly of ratchet wheel 155 is a pinion 156 concentrically mounted on axle 143 and free to rotate thereabout. The inner face of pinion 156 carries a radial arm 157, having pivotally attached to the free end of said arm a pawl 158 cooperatively engaging the aforementioned ratchet wheel 155. Pinion 156 intermittently engages a vertical rack 159 mounted upon an inwardly offset bracket 160 depending from the forward end of tie bar 149. It may now be seen that each complete cycle of raising and 70 lowering the transfer carriage 140 will result in

a uni-directional quarter revolution of large driving sprocket 152.

Encircling sprockets 151 and 152 is a large endless band or chain 161 which is maintained under tension so that it is taut. Chain 161 carries equidistantly spaced thereabout a plurality of brackets 162 which are integral with the pairs of side links 163 thereat, as best seen in Figure 5 of the accompanying drawings. Brackets 162 carry retaining means or clips 164 pivotally mounted thereon by pins 171. The general construction of clips 164 is seen in Figures 3 and 5 while in the other views said clips are indicated by the center lines thereof, for purposes of clarity. Each of the clips 164 is comprised of a fixed jaw 165 (that is, 15 not capable of longitudinal movement with relation to the chain 161) and a movable jaw 166. Jaws 165 and 166 are each provided with a pair of inwardly bent integral offset ears, having aligned orifices therein and being pivotally interconnected by a pintle 167, retained in place by expanded ends thereon. The jaws of the clips are maintained in a normally closed position by the action of expansive springs 168, which force the gripping teeth 169 in intimate contact. The gripping faces of these teeth when desired are provided with corresponding pin point projections and depressions, or other surface irregularities to prevent slippage of the sheets of sensitized material therefrom. The fixed jaws 165 of each of 30 the clips 164 are provided with integral actuating arms 170, disposed transversely and inwardly with relation to the entire machine and longitudinally with respect to the clips 164. These arms 170 control the radial displacement of the clips 164 35 about the pins 171. Since clips 164 are associated essentially with the chain 161, their travel may be described by two opposed semicircles the inturned ends of which are joined by two parallel lines in a longitudinal vertical plane, and said clips may 40 be spoken of generally as being at one time in an active or down position, or at another time in an inactive, inverted or up position. There are two horizontal positions in which the clips are traveling from or to the active position.

When the clips 164 are in their active position, or over the developing tanks 113 to 120 inclusive they are subjected to a gentle radial oscillation in the following manner. The free ends of arms 170 are provided with studs and rollers thereon which 50 act as followers for a series of eccentric circular plate cams 172 mounted along a longitudinal shaft 173 suitably journaled at the ends thereof in a forward upright 174 and a rear upright 175. Uprights 174 and 175 project from base plate 21 and are an exact height so that when clips 164 come to rest in their loading or discharging position the tops of the said uprights contact arms 170 and properly align the clips in a true horizontal position. The shape of arms 170 is best seen in Figure 3 in which the lower arm shown is that belonging to the clip directly to the rear of the one shown in the loading position, from which last mentioned clip the arm 170 is deleted and the upright 174 is omitted to better display 60 the magazine and the clip loading mechanism.

At this point may also be noted a peculiarity of cam 176 which is concentrically mounted upon shaft 173 opposite the re-exposing box 125 so that the sheet of sensitized material within said box may remain at rest during re-exposure. Cam 176 may be replaced by an eccentric cam when a tank is substituted for box 125.

Shaft 173 operates at approximately 43 R. P. M. and derives rotation by means of a gear 177 75

mounted thereon forward of upright 175; said gear 177 engaging a gear 178 mounted on a short shaft 179. Shaft 179 is horizontally and longitudinally disposed and is journaled in uprights 180 and 181. The forward end of shaft 179 penetrates the forward upright 181 and terminates in a bevel gear 182 which meshes with another bevel gear 183 mounted upon the inner end of a transverse horizontal shaft 184. Shaft 184 is journaled in uprights 185 and 186, penetrating the latter to terminate in a sprocket 187 which is connected by a chain 188 to a sprocket 189 on the outer end of shaft 26.

The clips 164 when in their inverted or inactive position assume the position shown in Figure 3, caused by the off center weight of arms 170. The degree of tilt is controlled when the arms 170 come to rest against brackets 162. A shelf 141 integral with the tie bar 141 and shown only on Figure 3 serves a double function by carrying off water which has drained from the tilted clips and by conducting it over the tanks 113-120 and discharging said water into the trough 121 or other suitable outlet.

When clips 164 are in their active or down position and the transfer carriage 140 is raised, the off center weight of arms 170 causes the clips 164 to tilt and allow one corner of the sheet to hang lowermost. This facilitates the draining of excess solution from the surfaces of the sheet and reduces inter-tank pollution.

When the transfer carriage 140 is lowered the entrance of the sheet is likewise facilitated by the "one point lowermost" position of the sheet in that when damp the said sheet is comparatively limp and buckling is avoided, the point first entering the solution in the tank producing this effect.

The transfer carriage elevating mechanism

The transfer carriage 140 is elevated by the actuation of a double bell crank assembly 190 having a power arm 191 and front and rear load arms 192 and 193 respectively. Arms 192 and 193 form an angle of 180 degrees with each other while arm 191 is slightly outwardly offset and bisects this angle. Crank assembly 190 is pivotally mounted, by means of an integral transverse axle 194, in a bracket 195 depending from tie bar 149. The free ends of the load arms are connected by flexible chains to clevises 197 on bosses 146. The chains 196 rise vertically from said bosses and after passing over idler pulleys 198 approach each other to terminate at the load arms 192 and 193. Pulleys 198 are mounted proximate the ends of tie bar 149.

The free end of power arm 191 is pivotally connected to the upper end of a vertical link bar 199, in turn pivotally attached to the free end of a radial arm 200. Tie bar 149 is cut away slightly as indicated by numeral 201 to allow clearance when arm 191 is rotated. A horizontal transverse shaft 202 suitably journaled in uprights off base plate 21 carries radial arm 200 integrally on the outer terminal thereof and a gear 203 at the inner end thereof. Gear 203 engages an arcuate rack 204 concentrically mounted on the rear or load arm of a lever 205. Lever 205 has an integral collar medially thereof by which it is rotatably mounted on a short transverse shaft 206 which is journaled in two uprights off the base plate 21. The forward or power arm of lever 205 is provided with an offset stud and roller thereon which acts as a follower for the steep rise plate cam 207. Cam 207 is integrally mounted on shaft

102, inwardly of cam 101 and directly beneath shaft 27. Since shaft 102 operates at approximately 2 R. P. M. as set forth above, cam 207 through the mechanism just described, causes the transfer carriage 140 to rise during 3½ seconds, fall during 1½ seconds, and to remain stationary during 25 seconds, two complete cycles of oscillation being completed every minute.

The transfer carriage in its upper position is adapted to operate the control toggle arm 124' 10 of a valve 124 situated in the main water supply line 124 as shown in Figure 1. The free end of arm 124' is provided with a mounted stud and roller thereon which is actuated by tie-bar 142 when in the upper position thereof. Since the 15 machine always ceases operation with the transfer carriage 140 in its upper position, as will be described below, valve 124' is adjusted to close whenever the transfer carriage is in that position.

The clip loading mechanism

Situated immediately inward of the rear wall 40 of the magazine are a pair of upright contacting resilient rollers comprising an idler roller 208 and a driving roller 209. These rollers are 25 mounted on upright axles 210 projecting from shelf 62. Roller 209 is driven by means of a sprocket 211, a connecting chain 212, another sprocket 213 mounted on a vertical shaft 214, and the pair of bevel gears 216 and 217. Shaft 214 is journaled in a pair of overlying brackets 215 which project rearwardly from the skeletal framework adjacent thereto. Bevel gear 216 is mounted on shaft 214 while bevel 217 is mounted on the inner terminal of shaft 58.

Situated immediately opposite the point of engagement of rollers 208 and 209, and directly below one of the clips 164 when in its loading position is a small horizontal transverse shelf 218 suitably supported by shelf 62 at a height 40 thereabove slightly less than the width of a sheet of sensitized material, said support not being shown in the drawings. Shelf 218 is slotted longitudinally and centrally thereof, the slot communicating with the inner edge of said shelf. 45 Affixed to the under surface of shelf 218 and co-extensive with the edges of the aforesaid slot are a pair of upper sheet edge guides 219 while directly vertically therebelow are a similar pair of corresponding lower sheet edge guides 220 affixed to the upper surface of shelf 62. Upper guides 219 and lower guides 220 position the upper and lower edges respectively of a sheet of sensitized material after it has been ejected by the action of rollers 208 and 209, so that said sheet is in an exactly aligned position to be grasped by the said clip. The upper edge of said sheet projects through guides 219 and shelf 218 to allow a sufficient surface thereof to be grasped by said clip as best seen in Figure 5.

A right angle bracket 223 supported in an upright position by shelf 218 carries a face plate 224 on the forward vertical surface thereof, said plate being suitably shaped to conform to the rear face of the clip brackets 162. The function of bracket 223 and plate 224 is to prevent disalignment of the fixed jaws 165 when the movable jaw 166 is actuated by a transverse horizontal rod 225. Rod 225 is carried between two radial arms 226 and 227 which pivot about the point of attachment 65 thereof to two lugs 228 projecting from shelf 218. The outer radial arm 227 is extended upwardly and is pivotally attached to the forward end of a horizontal, longitudinally disposed, link bar 229. The rear end of link bar 229 is connected to the 70 75

clip unloading or discharging mechanism to be described below. Rearward motion of link bar 229 causes the rod 225, which thus acts as a crank, to open one of the clips 164 in the loading 5 position, while forward motion of said bar closes, or more specifically, allows the clip to close.

Link bar 229 is longitudinally reciprocated by a long vertical lever 230. The upper or load arm of lever 230 is slotted and connects with a pin 10 projecting outwardly from link bar 229 adjacent its forward end, while the lower end of lever 230 is provided with an integral stud and roller thereon which acts as a follower for a plate cam 231. Lever 230 is pivotally mounted medially thereof 15 on a bracket affixed to the adjacent skeletal frame, said bracket being omitted from the drawings. Cam 231 is mounted on the outer end of shaft 102.

The clip unloading mechanism

20 One of the clips 164 when it is in position to be unloaded lies directly below rear axle 144, and to the rear of a small rectangular shelf 232, horizontally and transversely disposed. Shelf 25 232 corresponds with plate 219 and supports an assembly identical with that described in connection with the clip loading mechanism comprised by rod 225, arms 226 and 227, and lugs 228. The arm which corresponds to arm 227 is 30 attached to the rear end of link bar 229. In addition, shelf 232 carries, directly forward of the last mentioned assembly, a pusher mechanism adapted to positively eject the sheet from the opened clip. This pusher mechanism comprises 35 a pair of fingers 233 radially affixed to a short transverse shaft 234 which is journaled in short upright brackets off shelf 232. The outer end of shaft 234 carries a cam 235 which is actuated by a finger 236 carried by link bar 229.

40 A contractile spring, interconnecting rear rod 148 and a small offset radial arm vertically depending off shaft 234 immediately inward of cam 235, serves to keep fingers 233 in inoperative position and to keep the cam 235 in cooperative 45 engagement with finger 236.

The dryer

Situated below a clip in its unloading position, is a gently curved plate 237, vertical at its upper 50 portion and diverging to the rear at its lower portion.

Numerals 238 and 239 designate a pair of vertical, longitudinally disposed, spaced parallel plates which project from base plate 21. Plates 55 238 and 239 carry trunnioned therebetween four transverse rollers 240, 241, 242, and 243. Rollers 240 and 241 are composed of any suitably resilient material, and the peripheries thereof engage each other at a point proximate the lower edge of 60 curved plate 237. Rollers 240 and 241 act as wringers and the liquid which they squeeze from the sensitized sheet as it passes therebetween falls into the trough 121 therebelow. Rollers 242 and 243 are encircled by a continuous belt 244 65 composed of any suitable material such as canvas, while between the inner surfaces of said belt and between said rollers is an enclosed electrical heater 245. The upper and lower walls of heater 245 contact the inner face of the belt 70 244, thereby not only drying the sensitized sheet by direct conduction and radiation of heat thereto, but by drying the belt itself, since the belt is of absorbent construction.

75 Roller 243 is an idler, while roller 242 is driven by a sprocket 246 mounted on the outer end of

its spindle, a connecting chain 247, and a sprocket on the outer end of the spindle of roller 240. Roller 241 is an idler, while roller 240 derives rotation through a sprocket 248, a chain 250, a sprocket 251, a transverse horizontal short shaft 5 252, a gear 253 and a pinion 254 on shaft 184. Sprocket 248 is mounted on the inner end of the spindle of roller 240. Sprocket 251 and gear 253 are mounted on shaft 252 which is suitably journaled in uprights off the base plate 21. Rollers 240 and 242 operate at approximately 3 R. P. M.

Proximate the roller 243 and at the rear of the machine is an irregularly shaped receptacle 246 adapted to receive finished sensitized sheets. It is substantially wider than belt 244, and is lacking the outer side wall thereof. This side opening communicates with a similar opening in the casing of the machine which is closed by a flexible light-proof curtain, and through which opening the finished pictures may be obtained. The receptacle is designed to prevent the entrance of light therethrough into the machine casing.

The timing mechanism

In order that the heat generated by heaters 137, 138 and 245 and/or bulb 135, and in order that the entire developing machine shall continue to function until all of the separate sensitized sheets that have been deposited upon conveyor belt 28 are completely finished and ejected 30 into receptacle 246, a timing mechanism is provided and located on an intermediate shelf 255. Shelf 255 is situated forwardly and to one side in the machine as indicated by the dotted outline thereof shown on Figure 2, and is independently supported by the skeletal framework adjacent thereto.

Broadly speaking, the timing mechanism is so constructed that it normally sets a trigger 287 which keeps the electrical circuit closed to the main motor 22 whenever a spiral spring 256 is 40 allowed to unwind. The release of spring 256 occurs whenever a solenoid 257 is energized, which energization takes place simultaneous with the depositing of each separate exposed sensitized sheet on conveyor belt 28. As soon as motor 22 operates, however, it begins to rewind spring 256 and after approximately 7½ minutes the spring is rewound and the trigger mechanism is unlatched to its "off" position, thereby opening 50 circuiting motor 22. Any single energization of solenoid 257 sets the trigger 287 and restarts the complete cycle.

Rotation of a shaft 258 occurs at approximately 2 R. P. M. by means of a sprocket 259 on the forward end thereof, a chain 260, and a sprocket 261 on shaft 27. Shaft 258 is horizontally and longitudinally disposed above shelf 255, and is journaled in three uprights 262 which each carry pivotally mounted thereon one of the mercury switches 263, 264, and 265. Switch 263 is in series with heater 245; switch 264 with heaters 137 and 138; and switch 265 is in series with the incandescent bulb 135. Shaft 258 carries mounted thereon four cams 266, 267, 268, and 269. 60 Switches 263, 264 and 265 are pivotally mounted and springs 263' rotate them so that pins projecting from the side walls thereof act as followers for cams 266, 267, and 268, respectively, said cams being uniform with each other. Cam 269 actuates the lower arm of a vertically disposed rock lever 270, while the upper arm thereof is connected by a link 271 to the free end of a radial arm 272. Lever 270 is pivotally mounted on an upright 273 projecting from shelf 255, while 70 75

radial arm 272 is mounted upon a horizontally and longitudinally disposed stationary axle 274, being free to rotate thereabout. The lower end of lever 270 acts as a follower for cam 269 owing to the contraction of a helical spring 275 connecting the upper ends of radial arm 272 and an upright 276. Arm 272 carries a spring controlled driving pawl 277 mounted thereon which together with a spring controlled retaining pawl 278 serves to transmit the rotation of shaft 258 into an intermittent uni-directional rotation of a ratchet wheel 279. Pawl 278 is mounted on the rear face of upright 276, opposite ratchet wheel 279 which is free to rotate on axle 274. Proximate the periphery of wheel 279, and projecting perpendicularly from the rear face thereof is an annular row of spaced pins 280. Affixed to axle 274 and immediately rearward of wheel 279 is the spiral spring 256. The outer end of spring 256 is affixed to the forward face of a disc 281 and thus serves to rotate said disc in a counter-clockwise direction as viewed in Figure 12, whenever disc 281 is disengaged from wheel 279. A lug 292' projecting from shelf 255 serves as a stop against which the pin 292 strikes to limit the counter-clockwise rotation of disc 281. The outer end of spring 256 is attached to the forward face of disc 281 by means of a pin 282 perpendicularly projecting from the said forward face. The disc 281 constitutes an enlarged flange of a sleeve 283, adapted to rotate about the axle 274, and capable of limited longitudinal movement therealong. Mounted upon said sleeve and immediately to the rear of disc 281 is a cam 284 adapted to actuate a follower 285 which projects from the front face of a mercury switch 286 in series with the motor 22. A spring 286' causes follower 285 to contact cam 284. When cam 284 rotates counter-clockwise as viewed in Figure 13, it strikes a trigger 287 by means of a lug 288 perpendicularly projecting from the rear face of said cam. When cam 284 rotates clockwise it raises switch 286 to its "on" position where said switch is latched by the trigger 287. Trigger 287 is mounted on an offset arm 289 of an upright 290 which carries the switch 286 pivotally mounted thereon. An expansive spring 291 about the rear portion of axle 274 serves to force the sleeve 283 forward so that pin 292 projecting from the front face of disc 281 engages one of the interstices of the row of pins 280, while a lever 293 having a bifurcated free end riding on the sleeve 283 is adapted to strike a collar 294 mounted on the rear end of sleeve 283 and thereby disengage disc 281 and wheel 279 with the rearward displacement of said sleeve. Lever 293 is adapted for movement in a horizontal plane by the pivotal mounting of the outer end thereof on an upright 294, the actuation of said lever being accomplished by the link 295 attached to the armature of solenoid 257. The contractile spring 296 of the trigger 287 is anchored in lever 293.

It is to be noted at this point that the radial position of cam 269 on shaft 258 is correlated with the radial position of cam 207 on shaft 102 so that the machine comes to rest with the transfer carriage 140 in its elevated position, and cams 266, 267, and 268 elevating switches 253, 264, and 265 to their "off" position, thus opening all electrical circuits and closing the water supply.

General operation

Exposed sheets of sensitized material, preferably rectangular in shape, are deposited on the conveyor belt 28 with the greatest length of the

sheets transversely thereof, and are carried downwardly by the said belt and deposited in the magazine inlet chamber 35, long edge first. Where for some reason a sensitized sheet is deposited on belt 28 with its greatest length 5 parallel to the belt, or at any angle therewith not a right angle, rollers 42 turn it about by contacting the edges thereof. The narrowest width of the upper mouth of the chamber 35 is less than half the length of a sensitized sheet, so that the center of gravity of a sheet coming down the conveyor prevents it from pitching head first into chamber 35.

The oscillations of curved plate 49 jog the sheet so that it falls from chamber 35 into the magazine 41 where fingers 54 push the sheet rearwardly with its lower edge resting on shelf 62. The resilient facing contacts the upper edge of the sheet, rising momentarily when the fingers 54 enter the magazine. As fingers 54 enter the magazine, the dogs 63 rise to allow the sheet edge to pass rearwardly thereunder, and then these dogs fall to retain the sheet in position as fingers 54 withdraw. As other sheets are deposited on belt 28, they too are carried through the chamber 35 and are stacked up edgewise and consecutively in front of those already in the magazine.

As soon as an empty clip 164 is positioned opposite rollers 208 and 209, compressor plate 90 moves rearward thus forcing the rearmost sheet 30 in the magazine into contact with the laterally reciprocating resilient plate 69, which as it moves outwardly of the magazine 41 carries the rearmost sheet out of the magazine so that it may be pulled between the said rollers and fed into the awaiting 35 open jaws of the clip 164.

Resilient plate 69 is composed preferably of rubber and actuates the rearmost sensitized sheet because of the frictional or adhesive qualities of said plate. Plate 81 is similarly composed preferably of rubber and grips the edges of all of the sheets stacked within the magazine, but allows the rearmost sheet to move because the action of plate 69 has a more effective grip on the flat surface of said rearmost sheet, while the frictional engagement of the front face of the rearmost sheet and the rear face of the sheet directly in front is less than the frictional engagement of plate 81 on the edge of the last mentioned sheet.

Although plate 69 is constantly in motion, it only affects sheets which are brought into intimate contact therewith by the action of compressor plate 90. The latter plate moves rearward only when an open clip is in position to be loaded, which occurs every 30 seconds. Simultaneous with the rearward movement of plate 90, the curved plate 49 is raised so that it closes the bottom opening of the magazine inlet chamber 35 thus effectively preventing sheets from falling into the magazine while the actual clip 60 loading operation is taking place.

The clip 164 then closes upon the upper edge of the sheet and grips it, while the transfer carriage 140 consecutively immerses the gripping teeth 169 and the sheet therebetween in each of the tanks 113 to 120, and inserts it into the box 125. While the sheets are immersed in the developing solutions they are subjected to gentle agitation owing to the action of cams 172 on arms 170, which thereby agitates the solutions which as is 70 well known in the art expedites the development process and assures uniformity of chemical action.

As is obvious to those skilled in the art, the solutions in the various tanks may be arranged in any suitable manner. Those tanks desired 75

as washing tanks have the petcocks 122 thereon opened, and the water inlet pipe valves adjusted so that a constant level of circulating water is maintained. The position of the petcocks at the 5 bottom of the tanks allows the water made heavy by the chemicals dissolved therein to flow out by the action of gravity. Those tanks desired to contain chemical solutions have the petcocks thereon closed and are filled manually. When, 10 however, it is desired to flush and refill these tanks with fresh solutions, it is only necessary to open the petcocks and the water inlets thereabove to completely clean them preparatory to refilling.

When a clip 164 is placed within the re-exposing 15 box 125 the notched edge of gate 126 overlaps gate 127 and encircles the gripping teeth 169 directly above the sensitized sheet thereby promoting a light-proof seal at this point. This prevents light escaping from box 125 and fogging other sheets 20 in different stages of the development process.

The clip upon reaching its discharging or unloading position is opened and the sheet falls therefrom. Simultaneous with the discharging 25 operation another clip is loaded at the loading position. Where the sheet tends to stick to the clip owing to the adhesion of the gelatine coating thereon or for any other reasons, said sheet is forceably ejected by means of the fingers 233. The sheet is then wrung and dried as set forth 30 above and finally deposited in receptacle 246.

The machine as disclosed shows timing of the various operations to permit a separate sheet to be loaded into the clips every 30 seconds and a complete picture to be produced in about 6 35 minutes. The timing mechanism as set for a 7½ minute period of operation allows a sufficient margin of time to completely finish all of the pictures if they are not placed upon conveyor 28 at a greater frequency than one every 30 seconds. This timing has been found ample in practice 40 as at least 30 seconds are consumed in posing the subject, and adjusting the portrait lights. Where however, exposed sheets of sensitized material are deposited on the conveyor 28 in greater frequency, the timing mechanism may be altered to 45 increase the period above 7½ minutes or auxiliary means may be included to re-energize solenoid 257 so that all of the sheets deposited in the magazine 41 may be completed.

Furthermore, this machine is adapted for use 50 as an automatic developing machine working independently of a movable camera, or in conjunction with a fixed camera, in which case the angularly disposed top wall of the casing may be level instead, and some of the feeding mechanism (for example: belt 28 and/or rollers 42) may be dispensed with.

I wish it distinctly understood that variations 55 in the materials, construction, integration, and arrangement of the parts and assemblies may be indulged in without departing from the spirit of the invention or the scope of the appended claims.

I claim:

1. In an automatic machine for finishing and 60 developing sheets of sensitized material; a magazine adapted to stack said sheets horizontally on edge therewithin; the magazine having a friction plate adapted to engage the edges of said sheets and retain said sheets within the magazine; and discharging means associated with the 65 magazine to discharge single sheets in the same order in which said sheets are deposited therein; and a transfer carriage adapted to advance said sheets through the process of development and having a movable endless band with sheet 70

retaining means thereon for grasping said sheets; and mechanism for actuating said discharging means and said sheet retaining means whereby a sheet discharged from said magazine is received by said retaining means.

2. In an automatic machine for finishing and developing sheets of sensitized material; a magazine adapted to stack said sheets horizontally on edge therewithin, comprising stationary side walls and bottom, a movable front wall, and a stationary rear wall, a pusher finger penetrating said movable wall and adapted to reciprocate therethrough, a movable dog situated adjacent the said rear wall, and means to actuate said finger and said dog in synchronism whereby said sheets are retained stacked between said dog and said stationary rear wall in the order in which they are deposited in the magazine, and a transfer carriage adapted to advance said sheets through the process of development and having a movable endless band with a plurality of sheet retaining means thereon for grasping said sheets, and mechanism for actuating said ejecting means and said sheet retaining means whereby a sheet ejected from said magazine is received by the 25 retaining means.

3. In an automatic photographic developing machine for sensitized sheets; a magazine and a feeder therewith including an oscillating plate, a transfer carriage having a movable endless band 30 with a plurality of spaced sheet retaining means thereon, means to impart unidirectional intermittent displacement to said band whereby each of the retaining means is consecutively positioned opposite said magazine, and mechanism to 35 actuate said feeder in correlation with the positioning of the said retaining means, said mechanism comprising a pusher plate adapted to press a sensitized sheet into contact with said oscillating plate.

4. In an automatic photographic developing machine for sensitized sheets; a transfer carriage having a movable endless band; a plurality of sheet retaining means independently pivotally mounted on said band in fixed spatial relation; elevating mechanism for vertically reciprocating said carriage; agitating mechanism, independent of said elevating mechanism, to selectively agitate less than all of said retaining means.

5. In an automatic machine for developing and 40 finishing sheets of sensitized material, a transfer carriage adapted to advance said sheets through the process of development and having a movable endless band with a plurality of sheet retaining means thereon for grasping said sheets, said sheet retaining means being independently 45 pivotally mounted and having a radial extension arm affixed thereto whereby the center of gravity occurs to one side of the pivot so that a rectangular sheet held by said means will hang with one corner lowermost.

6. In an automatic machine for developing and finishing sheets of sensitized material, a transfer carriage adapted to advance said sheets through the process of development and having 50 a movable endless band with a plurality of sheet retaining means thereon for grasping said sheets, said sheet retaining means being independently and pivotally mounted and having a radial extension arm affixed thereto whereby the center 55 of gravity occurs to one side of the pivot so that a rectangular sheet held by said means will hang with one corner lowermost, and means to actuate said arm whereby the retaining means are 60 correspondingly agitated.

7. In an automatic machine for finishing and developing sheets of sensitized material: a magazine, a magazine inlet chamber having a movable gate adapted in the closed position thereof to retain sensitized sheets within the said inlet chamber and in the open position thereof to permit said sheets to travel to said magazine, a feeder associated with the magazine for ejecting sheets therefrom, a transfer carriage having a movable endless band with a plurality of spaced sheet retaining means thereon, means to impart unidirectional intermittent displacement to said band whereby each of the retaining means is consecutively positioned adjacent the magazine, mechanism to actuate said feeder in correlation with the positioning of the said retaining means whereby a sheet may be fed to one of the retaining means, and means to move the gate of the magazine inlet chamber into its closed position, thereby preventing the influx of sensitized sheets into the magazine, while the feeder is in operation feeding a sensitized sheet into one of the sheet retaining means.

8. In an automatic photographic developing machine for sensitized sheets: a magazine, a magazine inlet chamber having a movable gate adapted in the closed position thereof to retain sensitized sheets within said inlet chamber and in the open position thereof to permit said sheets to travel into said magazine, a feeder associated with the magazine and including a movable plate, a transfer carriage having a movable endless band with a plurality of spaced sheet retaining means thereon, means to impart unidirectional intermittent displacement to said band whereby each of the sheet retaining means is consecutively positioned adjacent the magazine, mechanism to actuate said feeder in correlation with the positioning of the said sheet retaining means, said mechanism including a pusher plate adapted to press a sensitized sheet into contact with said movable plate whereby a sheet may be fed to one of the sheet retaining means, and means to move the gate of the magazine inlet chamber into its closed position thereby preventing the influx of sensitized sheets into the magazine while the pusher plate is displaced for the purpose of feeding a sensitized sheet out of the magazine.

50 9. In an automatic machine for finishing and

developing sheets of sensitized material: a magazine adapted to stack said sheets horizontally on edge therewithin; the magazine having a movable friction plate adapted in the engaging position thereof to frictionally engage and retain said sheets within the magazine and in the disengaging position thereof to allow additional sheets to be added to the stack; discharging means associated with the magazine to discharge single sheets in the same order in which said sheets are deposited therein; means to move the friction plate to its disengaging position when sheets are being placed in the magazine and to move said friction plate to its engaging position when the discharging means is discharging a single sheet from the magazine; a transfer carriage adapted to advance said sheets through the process of development and having a movable endless band with sheet retaining means thereon for holding said sheets; and mechanism for actuating said discharging means and said sheet retaining means whereby a sheet discharged from said magazine is received by said retaining means.

10. In an automatic photographic machine for developing sensitized sheets: a light-proof re-exposing box having a movable closure at the top thereof; a transfer carriage adapted for vertical reciprocation; a crank connected to said closure; a plate cam movable with the transfer carriage, the crank acting as a follower for said cam whereby vertical movement of the carriage results in movement of the closure.

11. In an automatic photographic developing machine for sensitized sheets: a transfer carriage having a movable endless band; a plurality of sheet retaining means independently pivotally mounted on said band in fixed spatial relation; loading and unloading mechanism for the sheet retaining means, said mechanism being stationary and fixed with relation to the loading and unloading positions of the sheet retaining means; elevating mechanism for vertically reciprocating said carriage; agitating mechanism independent of said elevating mechanism to agitate less than all of the said pivotally mounted retaining means, whereby the sheet retaining means when in the loading and unloading positions receive no agitation from the agitating mechanism.

SAMUEL HERSHBERG. 50
